York, N. Y., a corporation of Delaware

Application August 3, 1940, Serial No. 350,240

15 Claims. (Cl. 62—5)

Our invention relates to refrigeration, and more particularly to refrigeration systems of the kind operated by heat.

It is an object of this invention to supply steam to a jacket or chamber associated with a heat receiving part of refrigeration apparatus, such jacket having a vent to atmosphere, and controlling the supply of steam so that at heat inputs less than a predetermined maximum a varying quantity of air can enter the interior of the jacket to form an air blanket about portions of the heat receiving part. In the present embodiment the air blanket is arranged to be formed about the upper part of the jacket or chamber in which are disposed a plurality of riser tubes through which liquid is raised by gas or vapor-lift action, the vapor being formed and the liquid being lifted due to heating by the steam. By controlling the rate of flow of steam to the jacket, more or less of the riser tubes can be blanketed off with air and out of direct contact with the steam, so that the effective tube surface area heated by the steam can be varied to effect regulation of the rate at which vapor is formed in the riser tubes and also the rate at which liquid is lifted or raised therethrough.

The invention, together with the above and other objects and advantages thereof, will be better understood from the following description taken in connection with the accompanying drawings forming a part of this specification, and of which:

Fig. 1 is a view more or less diagrammatically illustrating a refrigeration system embodying the invention; and

Fig. 2 diagrammatically illustrates an air conditioning system with which the refrigeration system in Fig. 1 is associated.

Referring to Fig. 1, the present invention is embodied in a two-pressure absorption refrigeration system like that described in our application Serial No. 239,762, filed November 10, 1938. A system of this type operates at low pressures and includes a generator or expeller 10, a condenser 11, an evaporator 12, and an absorber 14 which are interconnected in such a manner that the pressure differential in the system is maintained by liquid columns.

The disclosure in our aforementioned application may be considered as being incorporated in this application, and, if desired, reference may be made thereto for a detailed description of the refrigeration system. In Fig. 1 the generator 10 includes an outer shell 15 within which are disposed a plurality of vertical riser tubes 16.

5 having the lower ends thereof communicating with a space 17 and the upper ends thereof extending into and above the bottom of a vessel 18. The space 19 within shell 15 and about the tubes 16 forms a steam chamber 19 to which steam is supplied through a conduit 20 from a boiler 21.

10 The boiler 21 is provided with a plurality of fire or heating tubes 22 into the lower ends of which are adapted to project the flames produced by burners 23. A combustible fuel is delivered from a source of supply through conduits 24, control devices 25 to be described presently, and conduits 26 to the burners 23. Tubes 27 are connected to the conduits 24 and terminate in the vicinity of burners 23 to provide a pilot flame for each burner when its associated control device 25 operates so that fuel will flow to the burner. As shown most clearly in Fig. 2, the heating tubes are arranged alongside each other and the burners are located at the front of the steam boiler 21. The upper end of each heating tube 22 joins a flue or riser 28 (Fig. 1) through which warm gases pass into the atmosphere from the boiler 21. A suitable hand control valve 29 is provided in conduit 20 so that manual control of the steam flow to generator chamber 19 can be effected. A trap conduit 20a is connected to the lower end of shell 15 to provide a drain for condensate formed in chamber 19.

15 The system operates at a partial vacuum and contains a water solution of refrigerant in absorption liquid, such as, for example, a water solution of 40% lithium chloride by weight.

20 When steam is supplied through conduit 20 to chamber 19, heat is applied to tubes 16 whereby water vapor is expelled from solution. The absorption solution is raised by vapor-lift action with the expelled water vapor forming a central core within an upwardly rising annulus of the solution. The expelled water vapor rises more rapidly than the solution and solution follows the inside walls of tubes 16.

25 The water vapor flows upward through the tubes 16, vessel 18, conduit 30, vapor separating chamber 31, and conduit 32 into condenser 11 in which it is liquefied. The condensate formed in condenser 11 flows therefrom through a U-tube 33, flash chamber 34, and conduit 35 into evaporator 12.

30 The water supplied to evaporator 12 vaporizes therein to produce a refrigerating or cooling effect. The vapor formed in evaporator 12 passes through tubes 36 and 37 into a manifold 38 which is connected to absorber 14. To prevent

disturbances in evaporator 12, the flash chamber is provided to take care of any vapor flashing of liquid being fed to the evaporator through U-tube 33. The flashed vapor formed in the initial cooling of the liquid flowing from the condenser passes through a conduit 39 to manifold 38 and mixes with the vapor formed in evaporator 12.

In absorber 14 refrigerant vapor is absorbed into concentrated absorption solution which enters through a conduit 40. The water vapor absorbed into solution dilutes the latter, and the diluted absorption solution flows through a conduit 41, a first passage in liquid heat exchanger 42, a conduit 43, vessel 44, and a conduit 45 into the lower space 17 of generator 10. Water vapor is expelled out of solution in generator 10 by heating, and the solution is raised by vapor-lift action in vertical tubes 16, as explained above. Any liquid separated from vapor in separating chamber 31 flows through a U-trap 46 back to vessel 18.

The absorption solution in vessel 18 is concentrated since water vapor has been expelled therefrom in generator 10. This concentrated solution flows through a conduit 47, a second passage in liquid heat exchanger 42, and conduits 48 and 49 into absorber 14. This circulation of absorption solution results from the raising of liquid by vapor-lift action in vertical riser tubes 16, whereby the solution can flow to the absorber 14 and return from the latter to the generator 10 by force of gravity.

To provide a vent for conduit 48 the upper end thereof is connected by a conduit 49 to manifold 38. The upper end of vessel 44 is connected by a conduit 50 to vessel 18, whereby the pressure in the vessel 44 is equalized with the pressure in upper part of generator 10 and condenser 11. The lower parts of evaporator 12 are connected by conduits 51 and 51' to an upper part of vessel 44, so that unevaporated liquid may be drained from evaporator 12 into vessel 44.

The heat liberated with absorption of water vapor in absorber 14 is transferred to a suitable cooling medium, such as water, for example, which is supplied through a conduit 52 and flows upwardly through coils 53 and 54. The coils 53 and 54 are connected by a conduit 55 to condenser 11, so that the same cooling medium may be utilized to cool absorber 14 and condenser 11. The cooling medium flows from condenser 11 through a conduit 56.

The system operates at low pressures with the generator 10 and condenser 11 operating at one pressure and the evaporator 12 and absorber 14 operating at a lower pressure, the pressure differential being maintained by liquid columns. Thus, the liquid column formed in the tube 33 maintains the pressure differential between condenser 11 and evaporator 12. The liquid column formed in conduit 41 maintains the pressure differential between the outlet of absorber 14 and generator 10, and the liquid column flow in conduit 48 and parts connected thereto including conduit 47 maintains the pressure differential between the inlet of absorber 14 and the upper part of generator 10. The liquid column formed in conduit 51 maintains the pressure differential between evaporator 12 and vessel 44 which is pressure-equalized through conduit 50 with the upper part of generator 10. In operation, the liquid columns may form in conduits 41, 47, and down-leg of tube 33 to the levels x, y, and z, for example. Conduit 33 is such that restriction of

gas flow is effected without appreciably restricting flow of liquid. The liquid column formed in vessel 44 and conduit 45 provides the liquid reaction head for raising liquid in the vertical tubes

5 16 by vapor-lift action.

The vessel 44 is of sufficient volume to hold the liquid differential in the system and is of such cross-sectional area that the liquid level therein does not appreciably vary, so that a substantially 10 constant reaction head is provided for lifting liquid in generator 10. The vessel 44 is located below absorber 14 such a distance that, for the greatest pressure differential occurring between absorber 14 and the upper part, or vapor space, 15 of generator 10 during operation of the system, the liquid column formed in conduit 41 is below the lower end of absorber 14.

The evaporator or cooling element 12 is arranged in a conduit 57 of an air conditioning system, as shown in Fig. 2. The duct 57 is connected to a suitable blower 58, whereby air is withdrawn from an enclosure 59 through a duct 60 and passes in thermal exchange relation with evaporator 12 in duct 57. The refrigerant supplied to evaporator 12 vaporizes therein to produce a cooling effect, as pointed out above, with consequent absorption of heat from the air passing over the exterior surfaces of the evaporator. The cooled air flows through the blower 58 into a duct 61 from which the cooled air is discharged into the enclosure 59.

As shown in Figs. 1 and 2, each of the control devices 25 includes a solenoid coil 62 formed to receive a plunger 63 to which is fixed a valve 64. When a solenoid coil 62 is electrically energized, the plunger 63 and valve 64 are raised against the force of gravity, whereby the valve 64 is moved to its open position so that fuel can flow from the conduit 24 past the valve into conduit 26 and thence to burner 23. When a solenoid coil 62 is deenergized, the plunger 63 and valve 64 fall by gravity, whereby the valve is moved to its closed position to shut off flow of fuel to the burner. Each control device 25 is provided with a coil spring 65 to ensure downward movement of the plunger 63 when the solenoid coil 62 is deenergized.

Any suitable control may be provided for controlling the control devices 25 and hence the flow of fuel to burners 23. Although we do not wish to be limited thereto, we have illustrated a control arrangement like that described in application Serial No. 350,237, of A. R. Thomas, filed August 3, 1940. In this type of control the burners 23 are controlled sequentially responsive to a temperature condition affected by the refrigeration apparatus.

As shown in Fig. 2, the solenoid coils 62 are connected to conductors 66 and 67 which are connected to a suitable source of electrical supply. One terminal of each coil 62 is connected by a conductor 68 to the conductor 66, and the other terminal of each coil is connected by a conductor 69, a switch 70, and a conductor 71 to the conductor 67. The switches 70 are of the snap-action type and include toggle arms 72 and 73 pivotally connected at their inner ends at 74 to a support, and a coil spring 75 connected to the outer ends of the arms.

Stops 76 are provided to limit movement of lower toggle arms 73 in one direction. When moved in the opposite direction the contacts 77 at the ends of toggle arms 73 cooperate with fixed contacts 78 to complete the circuits for the solenoid coils 62.

The upper ends of toggle arms 72 fit into recesses 79 formed in a slide bar 80 which passes through and is movable in suitable supports 81. The right hand end of slide bar 80 is formed with a recess 82 to receive the upper end of a lever 83 which is pivoted intermediate its ends at 84 to a frame 85. The lower end of lever 83 is pivotally connected to a rod 86 which is secured to an expandable and contractible bellows 87 having one end thereof fixed and secured to the frame 85. A spring 88 is interposed between the bellows 87 and the left hand end of frame 85.

The bellows 87 is connected by a capillary tube 89 to a thermal bulb 90 which is located in the enclosure 59. The bellows 87, tube 89, and bulb 90 constitute an expandable fluid thermostat containing a suitable volatile fluid which increases and decreases in volume with corresponding changes in temperature. The bellows 87 expands and contracts with increase and decrease in volume of the volatile fluid, and these movements of the bellows 87 are utilized to control the switches 70. In Fig. 2 both of the switches 70 are open and the solenoid coils 62 are deenergized, so that the valves 64 are in their closed positions and the supply of fuel to burners 23 is shut off. In the open positions of the switches 70 the contacts 77 and 78 are separated and the toggle arms 73 bear against the stops 76.

The control just described is effective to sequentially control the devices 25, and hence control the flow of fuel to burners 23, so that the evaporator or cooling element 12 will be capable of maintaining the air in enclosure 59 at a desired low temperature. When the air in enclosure 59, and hence the evaporator 12, tends to rise above the desired low temperature, the volatile fluid of the expandable fluid thermostat increases in volume and causes the bellows 87 to expand against the tension of coil spring 88. With expansion of bellows 87 clockwise movement is imparted to lever 83 about pivot 84, whereby slide bar 80 is moved toward the right.

As the slide bar 80 is moved toward the right, the upper toggle arms 72 move clockwise about the pivots 74, and, when the coil springs 75 are moved past the straight line positions of the toggle arms 72 and 73, the lower toggle arms 73 move with a snap-action toward the right to close contacts 77 and 78. The closing of contacts 77 and 78 completes the electrical circuits for the solenoid coils 62 of the control devices 25, whereby the valves 64 are moved to their open positions to permit flow of fuel to the burners 23. By providing the pilot flame tubes 27, the burners 23 are immediately ignited with opening of the valves 64, so that hot gases will pass through the heating tubes 22 to heat the water in boiler 21 to produce steam.

It will be noted in Fig. 2 that the upper toggle arms 72 of the switches 70 are at different angles with respect to the vertical. As slide bar 80 is moved toward the right, in the manner described above, the upper and lower toggle arms 72 and 73 of the left hand switch 70 will come to a straight line position ahead of the toggle arms of the right hand switch. When this occurs and the coil spring 75 of the left hand switch moves past the straight line position of the toggle arms, the lower toggle arm 73 will snap toward the right to close contacts 77 and 78 to complete the circuit for the left hand control device 25.

It will be evident, therefore, that when the air tends to rise above the low temperature at which it is desired to maintain the enclosure 59,

the movement of slide bar 80 toward the right due to expansion of bellows 87 will first cause one of the burners 23 to become effective to heat boiler 21. With continued movement of slide bar 80 toward the right, the toggle arms 72 and 73 of the right hand switch will reach a straight line position, and, when the coil spring 75 of this switch moves past the straight line position of the toggle arms, the lower toggle arm 73 will snap to the right to complete the electrical circuit for the right hand control device 25. By first closing one switch 70 and then the other switch 70 in the manner described above, the burners are controlled sequentially responsive to a temperature condition which is affected by the temperature of evaporator 12.

When the air in the enclosure 59 tends to rise above the desired low temperature, the bellows 87 may expand enough to cause one or both of the burners to become operative to effect heating of boiler 21. The steam produced by the boiler 21 due to heating by the burners 23 flows through conduit 20 to generator steam chamber 19, whereby an increased refrigerating or cooling effect is produced by the evaporator 12 which is transmitted to air flowing through the duct 51 to the enclosure 59.

Conversely, when the air in the enclosure 59, and hence the evaporator 12, tends to fall below the desired low temperature, the volatile fluid of the expandable fluid thermostat decreases in volume and causes the bellows 87 to contract. Contraction of bellows 87 imparts counter-clockwise movement to lever 83 whereby slide bar 80 moves toward the left. Under these conditions the upper toggle arms 72 move counter-clockwise about the pivots 74, and, when the coil springs 75 have moved past the straight line positions of the toggle arms in the opposite direction from that described above, the lower toggle arms 73 move with a snap-action toward the left with such movement being limited by the stops 76. This movement of the lower toggle arms 73 causes separation of contacts 77 and 78 to open the switches 70, so that the electrical circuits of the solenoid coils 62 are opened. This causes de-energization of the solenoid coils 62 and the valves 64 move to their closed positions to shut off flow of fuel to the burners 23. When this occurs, the heating of boiler 21 is decreased and the production of steam is reduced, so that the refrigerating or cooling effect produced by the evaporator 12 is also reduced.

Assuming that both of the switches 70 are closed, and that the slide bar 80 is moving toward the left due to contraction of bellows 87, the right hand switch 70 will open first to cause de-energization of the right hand control device 25. With continued movement of slide bar 80 toward the left, the other switch 70 will be opened, whereby both of the control devices 25 will be de-energized and flow of fuel shut off to both of the burners 23. However, the air in the enclosure 59 may fall below the desired low temperature such an amount as to cause only one of the switches 70 to open, so that one of the burners 23 will continue to effect heating of the boiler 21.

In accordance with this invention, the steam boiler system operates substantially at atmospheric pressure, so that self regulation is effected of the rate at which vapor forms in the generator riser tubes 16 and the rate at which absorption liquid is raised in the tubes by vapor-lift action. This is accomplished by providing a

steam vent 91 at the upper part of generator chamber 19 which permits air to enter the upper part of chamber 19 and blanket off part of the riser tubes 16 from direct contact by the steam at heat inputs less than maximum.

The steam boiler system is so proportioned and designed that at maximum heat input to the steam boiler 21 by both of the burners 23, and with full load on the evaporator 12 for a refrigeration system of a given capacity, the steam supplied to the chamber 19 fills the entire space of the latter. Further, under these conditions full length heating of the riser tubes 16 is effected by the steam with practically no steam passing through the vent 91 into the atmosphere. The condensate formed in chamber 19 collects in the bottom part thereof and is drained through trap conduit 20a. With all of the surfaces of tubes 16 heated by steam and effective to expel refrigerant from absorption solution, maximum capacity is obtained from generator 10 with vapor being formed in the tubes 16 and liquid being raised by the vapor at a maximum rate.

When the control described above has operated so that only one of the burners 23 is supplying heat to the steam boiler 21, the supply of steam to the generator chamber 19 is reduced. With the steam heating system operating substantially at atmospheric pressure due to the provision of the vent 91, the generator chamber 19 at heat inputs less than maximum will only be partly filled with steam. The steam supply at low load is such that only the bottom part of chamber 19 contains steam and the upper part thereof contains air which enters into the chamber from the atmosphere through vent 91. With the upper part of chamber 19 containing air, all of the surfaces of the tubes 16 are not heated by steam. Thus, the air blankets off the upper parts of the riser tubes 16 from direct contact with the steam so that full length heating of the tubes is not effected and the effective tube heating surface is reduced. With less heating of the tubes 16 along their lengths, less vapor is formed and less absorption solution is raised or pumped upward through the tubes 16 by vapor-lift action, and this is what is referred to herein as self regulation.

It should be understood that more than two burners 23 and control devices 25 can be employed so that a more sensitive control of the heat input to the boiler and of the steam supply to chamber 19 is effected. By providing more than two burners 23 to supply heat to steam boiler 21, therefore, the rate at which steam is supplied to the generator chamber 19 can be controlled between even narrower limits than with the two burners illustrated. In any event, it will be understood that the rate at which vapor is formed in riser tubes 16 and absorption liquid is raised in the tubes is proportional to the heat input, the extent to which the air blankets off the riser tubes 16 increasing and decreasing with variations in the heat input to the boiler 21.

At low loads on the refrigeration system when the rate at which refrigerant is expelled from absorption solution is reduced, the heat input is decreased and the absorption solution is more dilute than at heavier loads. Dilute absorption solution liquid tends to be raised more rapidly by vapor-lift action. However, by providing the vent 91 and permitting air to enter chamber 19 so that a part of the heating surface of the tubes 16 is blanketed off by the air, the circulation of

absorption liquid is such that it is more nearly proportional to the heat input.

In view of the foregoing, it will be evident that an improvement has been provided, whereby self-regulation of vapor formation and lifting of liquid by vapor-lift action is effected, by operating the steam boiler system associated with a generator or vapor expeller of a heat operated refrigeration system substantially at atmospheric pressure by the provision of a vent in the generator steam chamber.

While a single embodiment of the invention has been shown and described, it will be apparent to those skilled in the art that various modifications and changes may be made without departing from the spirit and scope of the invention, as pointed out in the following claims.

What is claimed is:

1. In a refrigeration system operated by heat and having a cooling element and a heat receiving part provided with a chamber, a boiler, a heater for heating said boiler to produce steam in the latter, said chamber being connected to receive steam from said boiler and having a permanent opening to atmosphere, and means to control said heater responsive to a temperature condition affected by said cooling element whereby air can pass through said opening from the atmosphere into said chamber with changes in heat input to said boiler by said heater.
2. In a refrigeration system operated by heat and having a heat receiving part provided with a chamber, a boiler having a heating tube, a fuel burner adapted to project its flame into said tube whereby hot gases pass through the latter to produce steam in said boiler, an electrical control device for controlling flow of fuel to said burner, said chamber having a permanent opening to atmosphere and being connected to receive steam from said boiler, and means responsive to a temperature condition affected by said refrigeration system for controlling operation of said device.
3. In a refrigeration system operated by heat and having a vapor expeller provided with a chamber and a riser tube extending vertically in the latter, means to supply steam to said chamber from a suitable source of supply to cause heating of absorption solution in said riser tube and effect expulsion of vapor from solution therein and raise liquid therethrough by vapor-lift action, said chamber having a permanent opening to atmosphere whereby air can pass into said chamber and partly fill said chamber to blanket off a portion of the heating surface of said tube from the steam when the supply of steam to the chamber is reduced, and a device for controlling the supply of steam to said chamber from the source of supply.
4. In a refrigeration system operated by heat and having a cooling element and a heat receiving part provided with a chamber, a boiler, a heater for heating said boiler to produce steam in the latter, said chamber being connected to receive steam from said boiler and having a permanent opening to atmosphere, and a device to control said heater.
5. In refrigeration apparatus for cooling an enclosure to which is connected a duct through which air is caused to flow to the enclosure, said refrigeration apparatus being operated by heat and having a cooling element in the duct and a heat receiving part provided with a chamber, a boiler, a heater for heating said boiler to produce steam in the latter, said chamber having a per-

manent opening to atmosphere and being connected to receive steam from said boiler, and a device responsive to changes in temperature in the enclosure to control said heater.

6. In a refrigeration system operated by heat and having a heat receiving part provided with a chamber, a boiler, a heater for heating said boiler to produce steam in the latter, said chamber having a vent permanently open to the atmosphere and being connected to receive steam from said boiler, the aforementioned parts being so constructed and arranged that at a definite rate of heat input to said boiler by said heater and a predetermined load on the refrigeration system the steam supplied to said chamber fills the latter substantially completely with the steam condensing in said chamber and substantially no flow of steam occurring through said vent, and means to control said heater to reduce the heat input to said boiler below said definite rate and hence reduce the supply of steam to said chamber, so that air can enter the interior of said chamber through said vent and blanket off part of said chamber from the steam to reduce the quantity of heat received by said heat receiving part.

7. A refrigeration system as set forth in claim 6 in which said means to control said heater operates responsive to a temperature condition affected by a part of the refrigeration system.

8. In refrigeration apparatus having an enclosure to which is connected a duct through which air is caused to flow to the enclosure, said refrigeration apparatus having a cooling element in the duct and a heat receiving part provided with a chamber, a boiler, a heater for heating said boiler to produce steam in the latter, said chamber having a vent permanently open to atmosphere and being connected to receive steam from said boiler, the aforementioned parts being so constructed and arranged that, for a definite heat input to said boiler by said heater and a predetermined load on said cooling element, the steam supply to said chamber fills the latter substantially completely with the steam condensing in said chamber and substantially no flow of steam occurring through said vent, and means responsive to fall of a temperature condition affected by said cooling element to reduce the heat input to said boiler below the definite rate and hence reduce the supply of steam to said chamber, so that atmospheric air can enter through said vent to partly fill the space of said chamber and blanket off a portion thereof from the steam to reduce the quantity of heat received by said heat receiving part.

9. In an absorption refrigeration system having an absorber and a generator provided with a liquid upflow conduit, a jacket disposed about said upflow conduit, a pipe connected to said jacket for supplying steam to the latter from a source of supply, the steam being effective to heat said upflow conduit to cause expulsion of vapor from absorption liquid therein and effect lifting of liquid therethrough by vapor lift action, said chamber having a permanent opening to atmosphere at a level above the region to which said pipe is connected to said jacket, and a device for controlling the supply of steam through said pipe from the source of supply to the jacket, whereby air can pass through said opening into said jacket from the atmosphere and blanket off a part of said upflow conduit from the steam to reduce the effective heating surface of said upflow conduit when the supply

of steam to the jacket is below a predetermined amount.

10. In a multiple pressure refrigeration system having a generator and a condenser adapted to operate at one pressure and an evaporator and an absorber adapted to operate at a lower pressure, and conduits connecting the aforementioned parts to provide circuits for circulation of refrigerant and absorption liquid, said generator having a chamber within which is disposed a vertically extending member connected at its lower end to receive absorption liquid from the absorber, a conduit connected to a lower part of said chamber for supplying steam thereto from a source of supply, said chamber having a permanently open atmospheric vent in the upper part thereof, the steam supplied to said chamber being effective to cause expulsion of vapor from absorption solution in said member and lifting of liquid therethrough by vapor lift action, said vent permitting air to enter the interior of said chamber from the atmosphere when the supply of steam to said chamber is below a predetermined maximum, and a device for controlling the supply of steam from the source of supply to said chamber through said conduit whereby the quantity of air within said chamber and the portion of said member blanketed by air from the steam is inversely proportional to the rate of flow of steam to said chamber.
11. A refrigeration system operated by application of heat and including a part having a heat transfer surface to which operating heat is applied for transfer to the system, a chamber having a wall formed by said heat transfer surface, and an inlet for admitting steam to said chamber, said chamber having a permanent opening to atmosphere at a point remote from said inlet so that air may flow in either direction through said opening and steam flowing from said inlet towards said opening comes in heating contact with said surface over an extent of said surface dependent upon the relative proportions of steam and air in said chamber.
12. A refrigeration system operated by application of heat and including a part having a heat transfer surface to which operation heat is applied for transfer to the system, a chamber having a wall formed by said heat transfer surface, said chamber being connected to receive steam at one point and a substantially constant pressure fluid at a second point remote from said first point so that steam admitted at said first point flows toward said second point in heating contact with said surface, the heating contact being over an extent of said surface dependent upon the quantity of steam in said chamber with respect to the quantity of constant pressure fluid therein, said constant pressure fluid being displaced from said chamber upon increase in quantity of steam therein, and said constant pressure fluid entering said chamber upon decrease in quantity of steam therein, the pressure in said chamber at all times being that of said constant pressure fluid.
13. A refrigeration system operated by application of heat and including a part having a heat transfer surface to which operating heat is applied for transfer to the system, a chamber having a wall formed by said heat transfer surface, and an inlet for admitting heating vapor to said chamber, said chamber having provisions for permanent breathing remote from said inlet so that a non-heating medium at substantially constant pressure may at all times flow into and out

of said chamber, and heating vapor flowing from said inlet towards said breather comes in heating contact with said surface over an extent of said surface dependent upon the relative proportions of heating vapor and non-heating medium in said chamber.

14. A refrigeration system operated by heat and having a heat receiving part provided with a chamber, said chamber having an inlet through which heating vapor is supplied to said chamber, said chamber also having provision for permanent breathing so that a non-heating medium at substantially constant pressure may at all times flow into and out of said chamber, and apparatus to control said supply of heating vapor to said chamber.

15. A refrigeration system operated by heat and having a cooling element and a heat receiving part provided with a chamber, said chamber having an inlet through which heating vapor is supplied to the chamber, said chamber also having provision for permanent breathing so that a non-heating medium at substantially constant pressure may at all times flow into and out of said chamber, and apparatus to control said supply of heating vapor to said chamber responsive to a temperature condition affected by said cooling element.

ALBERT R. THOMAS.
PHILIP P. ANDERSON, JR.
